UNITED STATES PATENT OFFICE.

LEWIS P. SITTIG, OF RIVER FOREST, ILLINOIS.

CHILD'S GARDEN.

Application filed April 6, 1922. Serial No. 549,977.

To all whom it may concern:

Be it known that I, LEWIS P. SITTIG, a citizen of the United States, residing at River Forest, in the county of Cook and State of Illinois, have invented certain new and useful Improvements in a Child's Garden, of which the following is a specification.

My invention relates to a child's garden and has for one of its objects the provision of a simple and efficient device which may be used indoors or out of doors for a small child's play yard or garden.

A further object is the provision of a simple and efficient device of the character mentioned which can be quickly and easily taken apart and put together.

A still further object is the provision of a simple and efficient device of the character mentioned which can be folded into a small space for transportation and storage.

Other objects will appear hereinafter.

An embodiment of my invention is illustrated in the accompanying drawing, forming a part of this specification, and in which—

Fig. 1 is a perspective view of a child's garden embodying my invention;

Fig. 2 is a plan view of a half of the garden folded for transportation or storage; and

Fig. 3 is a fragmental plan view showing a corner portion of the device with a part broken away to show underlying parts.

It is desirable in many homes to have a place for the small child's play things and where the child can play with them. This improvement is a device of this character which may be placed in any convenient part of the home or garden.

Referring more particularly to the drawing, I have indicated a garden, or the like, suitable for a child having four side portions with each of these side portions made up of a bottom rail 4, a top rail 5, and spindles or standards 6. The rails 4 and 5 may be of wood or any desired material. I prefer to form the spindle 6 of metal, but these may also be made of any desired material.

The spindles may be attached to the rail 4 and 5 in any desired manner. I have in-

dicated a construction in which the ends of the spindles are held by friction or an adhesive in recesses in adjacent sides of said rails 4 and 5. The recesses in which the spindles 6 are disposed may be formed of a size so that when the spindles 6 are forced into them a rigid construction will be had. Each of the four sides is substantially alike.

The sides of the garden preferably have 60 hinges 7 connecting the four sides in two pairs, as clearly indicated in Figs. 1 and 2. The hinges 7 may be of any approved construction. I preferably arrange the sides so that the rails 4 and 5 in one side will overlap the ends of the corresponding rails in the other side, as clearly indicated. This gives a construction in which the overlapping portions 8 help to brace the construction, thereby lending rigidity to it. 70

The other corners of the garden are held together by bolts or rods, preferably pivotally mounted. The connection last referred to comprises a part 9 attached to one of the rails 4 or 5 and has a hinge connection 10 75 at one end, to which is attached a rod or bolt 11. On each of the rods 11 is threaded a thumb nut 12. When the device is set up, as indicated in Fig. 1, the rods 11 on one pair of sides engages suitable openings 13 in 80 the other pair of sides, as indicated in Figs. 1 and 3. When it is desired to set up the device the parts are placed in the positions indicated in Fig. 1 and the pins inserted in the openings 13. The nuts are then adjusted into position to bind the parts tightly together. 85

When it is desired to take the device down for moving it about or for storing or shipping, the two sides of each pair of sides are folded together, as indicated in Fig. 2. The rods 11 are then inserted in the openings 13 in the same pair of sides. The nuts are then attached which bind the two sides of the pair tightly together, see Fig. 2. 95

This construction permits the device to be quickly and easily folded or as quickly and easily set up for use when desired.

I claim:—

A child's garden comprising a plurality 100 of side walls; hinges attached to adjacent ends of each set of two side walls connect-

ing said side walls in pairs, there being a transverse opening in one remote end of each pair of said side walls; and a pin pivotally connected to the other remote end of each pair of said walls, the pin on each pair of walls being adapted to engage the opening in another pair of walls when in one pos-

tion and adapted to engage the opening in its own pair of walls when in another position.

In testimony whereof I have signed my name to this specification on this 4th day of April, A. D. 1922.

LEWIS P. SITTIG.
